(57) CLAIM

The ornamental design for a garage door opener lense, as shown and described.

DESCRIPTION

FIG. 1 is a top, front perspective view of the garage door opener lense showing my new design;
FIG. 2 is a top, rear perspective view of the garage door opener lense showing my new design; and,
FIG. 3 bottom, rear perspective view of the garage door opener lense showing my new design.

The broken line showing is for illustrative purposes only and forms no part of the claimed design.
